HAIR DRYER

William J. Russell, Kensington, Conn., and Robert B. Fay, Brockton, Mass., assignors to Handy Hannah Products Corporation, Whitman, Mass., a corporation of Massachusetts

Filed July 21, 1958, Ser. No. 749,696

5 Claims. (Cl. 219—39)

This invention relates generally to hair dryers and more particularly to an improved construction for hair dryers which have provision for heating the air and which are of a size and weight suitable for hand-held use.

It is a general object of this invention to provide a hair dryer which is light in weight, rugged and easy to operate while being economical to manufacture and which incorporates improved air-flow and heat-transfer characteristics.

It is a further object of this invention to provide an improved arrangement for mounting the working parts of the dryer relative to each other and for supporting the working parts within a housing, so as to reduce manufacturing problems while improving useful air output.

It is a still further object of this invention to provide an improved housing and support structure for a hair dryer which produces a more compact and economical structure which is easy to operate, simple to service and adaptable to a variety of uses.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a side elevation of a preferred embodiment of this invention;

Fig. 2 is a front end view of the hair dryer shown in Fig. 1;

Fig. 3 is a rear end view of the hair dryer shown in Fig. 1;

Fig. 4 is a top plan view of the preferred embodiment with the top housing removed and part of the supporting structure cut away;

Fig. 5 is a partial side view of the preferred embodiment;

Fig. 6 is a cross section taken along the lines 6—6 of Fig. 5; and

Fig. 7 is a cross section taken along the lines 7—7 of Fig. 5.

Referring now to the drawings and particularly to Figs. 1, 2 and 3, it is seen that the hair dryer of the preferred embodiment has a generally tapered profile defined by top housing 1, bottom housing 2, and front intake grill 3. Bottom housing 2 has depending support 4 fastened thereto and pivotally connected to base 5 by fastener 6. Bottom housing 2 is provided with an aperture through which power cable 7 passes to energize the device, cable 7 being secured in a conventional manner to housing 2 by grommet 8.

2

Front intake grill 3 is of molded plastic in the preferred embodiment and is provided with a series of peripheral intake passages 10 and a series of front intake passages 11 defined by the molded grill work. Switch operating handle 12 is centrally located in front of grill 3 and is arranged in the preferred embodiment to be rotatable from "off" to "hot" or "cold" positions.

Base 5 can be placed on a supporting surface, and the operating position of the dryer can be changed by varying the pivotal position of the housing structure relative to the base structure. It is also noted that base 5 has a grip portion 14 which is dimensioned to fit comfortably in the user's hand in the event that hand-held use is desired.

15 Referring now to the internal structure and assembly features shown in Figs. 4 through 7, it is seen that main frame 16 is of generally cylindrical shape and is provided with three spaced inwardly extending mounting arms 17 to which three cooperatively positioned motor mounting arms 18, extending from front motor frame 35a, are secured by bolts 19. Supporting arms 17 and 18 are dimensioned so that shaft 20 of the electric motor, designated generally as 9, is coaxial with the longitudinal axis of cylindrical frame 16. Electric motor 9 is of the series type having a laminated field frame 21, a field winding 22 and a wound rotor 23, to which electrical connection is established through commutator 24 and brushes 25.

Shaft 20 of the electric motor has fan 32 secured adjacent its outer end and positioned forward of the inwardly extending air directing vanes 33 which are integrally formed with main frame 16 to reduce turbulence in the air drawn in through front grill 3 by rotation of fan 32.

35 Three spaced supporting arms 27 are secured to the forward end of frame 16 by screws 28 and serve to support front grill 3, fastened thereto by screws 29. The forward end of supporting arms 27 are welded or otherwise secured to plate 30 to which rotary switch 31 is fastened. The switch operating rod passes through front grill 3 and has operating knob 12 fastened thereto.

Rear frame 35, which is secured to laminated frame 21 and which acts as a rear bearing pedestal for shaft 20, also supports heater assembly designated generally as 36. Frame 37 of heater 36 is fastened to bracket 35b and also supports mutually perpendicular mica sheets 38 and 39 about which coiled resistance heater wire 40 is wrapped. The mica sheets 38 and 39 have a tapered profile and are provided with a series of notches 41 to retain resistance wire 40 in position. Electrical connection is established to one end of heater wire 40 through terminal 42 secured to mica sheet 39, and to the other end of heater wire 40 through fuse link 43, also secured to mica strip 39.

45 In the structure thus far described, it is seen that intake grill 3 and switch 31 are secured to the front of frame 16, and that heater 36 and electric motor 9 are secured to the rear of frame 16 so as to form a unitary assembly of the operating mechanism having a generally tapering profile and that this assembly is easily fabricated and assembled during manufacture.

The enclosure and support of the aforementioned assembly by the external housing and support members are accomplished in a unique and simple manner. As

65 most clearly seen in Figs. 4 and 6, frame 16 is provided with two outwardly directed longitudinally extending abutments 50 and 51. Upper housing 1 and lower hous-

ing 2 are provided with mating depressions or shoulders 50a, 50b, 51a and 51b which embrace abutments 50 and 51 when housing members 1 and 2 are joined. The abutting edges of housings 1 and 2 are provided with outwardly directed flanges 52 and 53 from which a series of tabs 52a and 53a are supported and which are bent over (see Fig. 7) to join the housings. Bottom housing 2 has bent-over ends 54 of support 4 secured thereto to form the point of pivotal connection for base 5. Rear grill 13 is carried by housing 2 and is trapped in position between the housings when assembled. Side channels 56 and 57 cover the mating abutments 52 and 53 of housings 1 and 2, and are secured thereto by bent over forward and rear end tabs 58. Rear end tabs 58 also engage and help to support rear grill 13. As clearly seen in Figs. 5 and 6, a space is provided between outer housings 1 and 2 and frame 16 so that electrical connecting wires can pass therethrough to establish connections between switch 31, motor 9 and heater 36.

In operation, when knob 12 is rotated to the "hot" position, motor 9 is energized to rotate fan 32 to draw cool air in through front grill 3. Because heater 36 is energized, the cool air, having its turbulence reduced by vanes 33, passes around motor 9 and is directed by the interior surfaces of frame members 1 and 2 across the heater wire 40.

If motor 9 fails to rotate fan 32, fuse link 43 will melt to open the circuit and prevent overheating. When knob 12 is rotated to the "cold" position, heater 36 is not energized and motor 9 moves cold air out of rear grill 13.

The tapered configuration of heater 36 provides more efficient exposure of the hot surfaces of wire 40 to the air passing therethrough, thereby to heat the air more efficiently. Since cool air is drawn over switch 31 and motor 9 regardless of switch position, the operation of these elements is measurably improved. Of course, because of the coaxial straight-line arrangement of the constituent parts of the assembly, straight-line air flow is achieved which, because of its efficiency, enables a greater air flow to be achieved.

The absence of a complicated supporting structure and the use of lightweight materials enables the hair dryer to be light in weight and easily held by the user's hand for seemingly long periods of time. The location of the switch in the front intake grill is not only convenient to use but also insures that the switch will remain cool to touch during extended periods of operation. Thus, the resultant assembly is not only economical to achieve, effective, and rugged to use, but also presents a generally pleasing appearance which is most essential when sales to women are desired.

As many changes could be made in the above construction and many different embodiments of this invention could be made without departing from the scope thereof, it is intended that all matter contained in the above description or shown in the accompanying drawings shall be interpreted as illustrative and not in a limiting sense.

We claim:

1. A hair dryer comprising a cylindrical frame, a front bracket secured to said frame, a front grill supported by said front bracket, an electric switch centrally disposed in said front grill and supported by said front bracket, a rear bracket on said frame, an electric motor supported by said rear bracket and positioned so that the axis of said motor is coaxial with the axis of said frame, a propeller secured to the shaft of said motor for rotation therewith at a point within said cylindrical frame, said propeller being constructed to draw air through said front grill and around said switch, a heater support secured to said motor at a point opposite said rear bracket, a resistance heater secured to said heater support and symmetrically disposed about the axis of said frame, said grill, frame, motor and heater defining a unitary assembly,

and a housing dimensioned to substantially enclose and support said assembly, said housing engaging said frame and abutting said front grill.

2. A hair dryer comprising a hollow frame having a longitudinal axis, said frame having outwardly and longitudinally extending abutments formed thereon, an electric motor supported by said frame, the shaft of said motor being positioned coaxially with said frame axis, a propeller mounted for rotation with the shaft of said motor at a point within said hollow frame, a resistance heater mounted on said motor opposite to said fan and symmetrically disposed about said frame axis, said frame, motor and heater defining an assembly whose profile tapers from front to rear, and an external housing of tapered profile, said housing being formed in two pieces adapted to be joined in a plane parallel to said longitudinal axis, the abutting edges of said two pieces having depressions formed therein and dimensioned to engage said frame abutments when said pieces are joined thereby to support said frame within said housing.

3. A hair dryer comprising a hollow frame having a longitudinal axis, an electric motor supported by said frame, the shaft of said motor being arranged coaxially to said frame axis, a propeller mounted for rotation with the shaft of said motor at a point within said hollow frame, a bracket secured to said motor at a point on said motor opposite said frame support, a resistance heater secured to said bracket, said frame, motor and heater defining a unitary assembly, outwardly extending abutments formed on said frame, and an external housing, said housing being formed in two pieces adapted to be joined in a plane parallel to said longitudinal axis, the abutting edges of said two pieces having depressions formed therein and dimensioned to engage said frame abutments when said pieces are joined thereby to support said unitary assembly.

4. A hair dryer comprising a cylindrical frame having outwardly extending abutments thereon, said abutments extending in a direction parallel to the axis of said frame, a bracket secured to the front portion of said frame, a grill secured to said front bracket, a switch secured to said front bracket and having an operator extending through said front grill, an electric motor supported by said frame at the other end of said housing, said motor being supported so that its shaft is coaxial with said frame axis, a propeller mounted for rotation with the shaft of said motor at a point within said hollow frame, a bracket secured to said motor at a point opposite to said frame support, a resistance heater secured to said last-named bracket and symmetrically disposed about said frame axis, said grill, frame, motor and heater defining a unitary assembly, and a housing dimensioned to abut said front grill and to substantially enclose said assembly, said housing being formed in two pieces adapted to be joined in a plane parallel to said frame axis, the abutting edges of said two pieces of said housing having depressions formed therein and dimensioned to engage said frame abutments when said pieces are joined thereby to support said unitary assembly.

5. A hair dryer comprising a cylindrical frame having outwardly extending abutments thereon, said abutments extending in a direction parallel to the axis of said frame, a bracket secured to the front portion of said frame, a grill secured to said front bracket, a switch secured to said front bracket and having an operator extending through said front grill, an electric motor supported by said frame at the other end of said housing in a position wherein its shaft is coaxial with said frame axis, a propeller mounted for rotation with the shaft of said motor at a point within said hollow frame, a bracket secured to said motor at a point opposite to said frame support, a resistance heater secured to said last-named bracket and symmetrically disposed about said frame axis, said grill, frame, motor and heater defining a unitary assembly, a housing dimensioned to abut said front grill, to substantially enclose said assembly and to define an air outlet.

aperture, said housing being formed in two pieces adapted to be joined in a plane parallel to the axis of said frame, outwardly extending flanges formed at the abutting edges of said two housing pieces, said flanges having depressions formed therein and dimensioned to engage said frame 5 abutments when said pieces are joined thereby to support said unitary assembly, a rear grill positioned in said air outlet aperture, and a pair of flange enclosing channels engaging the front and rear edges of said housing and supporting said rear grill.
